(57) **CLAIM**

I claim the ornamental design for an outsole for a shoe, as shown and described

DESCRIPTION

FIG. 1 is a bottom plan view of an outsole for a shoe showing my new design;

FIG. 2 is a perspective view thereof;

FIG. 3 is a left side view thereof;

FIG. 4 is a right side view thereof;

FIG. 5 is a front view thereof;

FIG. 6 is a rear view thereof; and,

FIG. 7 is an enlarged cross sectional view taken along line 7—7 of FIG. 1.

The broken line showing a footwear-upper in FIGS. 2–6 illustrates the portion of the design that forms no part of the claim.
